UNITED STATES PATENT OFFICE.

SYVER LOE, OF MINNEAPOLIS, MINNESOTA, ASSIGNOR, BY DIRECT AND MESNE ASSIGNMENTS, TO LOE MULTIPLEX VOTING MACHINE COMPANY, OF MINNEAPOLIS, MINNESOTA, A CORPORATION OF MINNESOTA.

VOTING-MACHINE.

1,307,098.

Specification of Letters Patent. Patented June 17, 1919.

Application filed May 24, 1917. Serial No. 170,722.

To all whom it may concern:

Be it known that I, SYVER LOE, a citizen of the United States, residing at Minneapolis, in the county of Hennepin and State 5 of Minnesota, have invented certain new and useful Improvements in Voting-Machines; and I do hereby declare the following to be a full, clear, and exact description of the invention, such as will enable others skilled 10 in the art to which it appertains to make and use the same.

This invention relates to multiplex voting machines of the general character disclosed and broadly claimed in my prior Patent 1,039,419, of date, September 24, 1912.

The present invention is directed chiefly to improvements in the machine setting and locking mechanism, to-wit, in the lever and lock mechanism controlled by a voter and 20 by the election judge or attendant; and in this respect, it is, particularly, an improvement on the mechanism disclosed and claimed in my prior Patent 1,158,518, of date, November 2nd, 1915, entitled "Multiplex voting machine."

In the accompanying drawings which illustrate the invention, like characters indicate like parts throughout the several views.

Referring to the drawings;

30 Figure 1 is a perspective view illustrating the present improved voting machine and showing three voters in three booths and an election judge or an attendant outside of the booth;

35 Fig. 1^a is an elevation with some parts broken away, showing the voting machine with the wings of the voting booth closed and cutting off access to the keys or register actuators;

40 Fig. 2 is a view chiefly in side elevation, but with some parts broken away and some parts in axial vertical section, showing the framework of the machine, the movable register support and certain of the operative devices, but with the register actuators and 45 registers and certain of the parts removed;

Fig. 3 is a detail in section on the line 3—3 of Fig. 4;

50 Fig. 4 is an enlarged section taken approximately on the line 4—4 of Fig. 2;

Fig. 5 is a plan view of the machine frame and showing certain levers and cranks to be

operated by the judge or attendant, other parts of the machine being removed;

Fig. 6 is a fragmentary view in vertical 55 section taken approximately on the line 6—6 of Fig. 5;

Fig. 7 is a fragmentary detail in section on the line 7—7 of Fig. 6;

Fig. 8 is a fragmentary section on the 60 line 8—8 of Fig. 6;

Fig. 9 is a detail in horizontal section on the line 9—9 of Fig. 6;

Fig. 10 is a plan view showing part of the upper frame structure and showing the 65 so-called voter's lever and associated parts, the annular top plate of the frame being removed;

Fig. 11 is a front or outside elevation of the parts shown in Fig. 10;

Fig. 12 is a view looking at the parts of Fig. 10 in a direction from the inner toward the outer side of the machine;

Fig. 13 is a detail in elevation showing a gear shifting device found in the vicinity of 75 the line 13—13 of Fig. 10;

Fig. 14 is a section on the line 14—14 of Fig. 13;

Fig. 15 is a detail of the ball and socket device found in the vicinity of the line 80 15—15 of Fig. 10;

Fig. 16 is a section on the line 16—16 of Fig. 15;

Fig. 17 is a plan view of an operating shaft used in connection with the parts 85 shown in Figs. 13 to 15, inclusive, and to which the voter's operating lever is applied;

Figs. 18 and 19 are vertical sections taken on the irregular lines 18—19 of Fig. 10, but 90 illustrating different positions of the parts;

Fig. 20 is a section taken approximately on the line 20—20 of Fig. 10, but showing the top plate of the upper frame structure and also showing in full, certain parts 95 which, in Fig. 10, are indicated by dotted lines only;

Fig. 21 is a detail in vertical section taken approximately on the line 21—21 of Fig. 4 and showing the oscillatory register sup- 100 port;

Fig. 22 is a plan view of the upper seg- mental head;

Fig. 23 is a plan view of the lower seg-

mental head of the supplemental frame of the register support;

Fig. 24 is a front or outside elevation showing a portion of the register support 5 and the registers or tallies applied thereto, some parts being broken away and some parts removed;

Fig. 25 is a horizontal section on the line 25—25 of Fig. 24;

10 Fig. 25^a is a horizontal section taken approximately on the line 25^a—25^a of Fig. 27;

Fig. 26 is a vertical section taken approximately on the irregular line 26—26 of Fig. 24;

15 Fig. 27 is a front or outside elevation showing a portion of the keyboard, upper portion of the frame structure, voter's actuating lever and coöperating signaling device;

20 Fig. 28 is a side elevation showing in detail the arm of the signaling device;

Fig. 29 is a section on the line 29—29 of Fig. 28;

25 Fig. 30 is a detail in side elevation showing a catch for coöperating with the arm of the signaling device;

Fig. 31 is a section on the line 31—31 of Fig. 30;

30 Fig. 32 is a detail in elevation showing a lock for the so-called register positioning crank or lever;

Fig. 33 is a vertical section taken approximately on the line 33—33 of Fig. 32;

35 Fig. 34 is a horizontal section on the line 34—34 of Fig. 33;

40 Fig. 35 is a view partly in elevation and partly in vertical section with some parts broken away, showing upper portions of the main frame and register support and particularly illustrating the action of a so-called total vote register;

Fig. 36 is a detail showing the total vote register foot in the same direction, but on a larger scale than in Fig. 35;

45 Fig. 37 is a section on the line 37—37 of Fig. 35;

Fig. 38 is a detail showing in side elevation one of the escapement devices and actuating bar of one of the so-called total vote 50 registers, said bar being in section; and

Fig. 39 is a fragmentary view in elevation showing one of the resister re-setting shafts and certain parts of one of the register actuating devices applied thereto.

55 Machine frame and support therefor.

The relatively fixed main framework of the machine is in the nature of a skeleton that outlines the form of a cylinder and, as 60 shown, it comprises an annular lower head frame 1, a similar annular upper head frame 2 and four tubular columns 3^a, 3^b, 3^c, and 3^d that rigidly connect the said frames. These upper and lower head frames have inwardly 65 converging spokes 3 that connect to hubs in

which the upright axle shaft 4 is journaled. (See particularly Figs. 2, 4, 5, 6 and 26.)

This machine frame may be supported in various different ways, but as shown, it is supported for vertical adjustments (see particularly Figs. 1 and 1^a) from the screw-threaded columns *a* of the truck *a*¹, by means and in a manner disclosed and claimed in my companion application filed of even date herewith and entitled "Truck, etc". Also, 70 the said main frame is preferably formed with hinged segmental doors or folding leaves *b* adapted, when the machine is out of use, to close up the machine to protect the register actuators or case and adapted, when the machine is in use, to be pulled out and used as part of the voting booths, all as more fully disclosed in my companion application filed of even date herewith, and entitled "Folding booth and frame for voting 75 machines".

Registers or tallies and support therefor.

The axial shaft 4 (see particularly Figs. 2 and 4 inclusive) carries the so-called tally support. This register support comprises upper main and supplemental register supporting frames. The said main register supporting frame is made up of upper and lower wheel-like heads 5 rigidly secured to the axle shaft 4 and connected at their outer portions, as shown, by three upright tie-rods 6. This frame 5—6, as is evident, must therefore partake of the rotary movements of the axial shaft 4, but has no vertical movement in respect thereto. The supplemental register supporting frame is made up of upper and lower segmental skeleton heads 7 and 7^a, respectively, that are tied together by a multiplicity of vertical channel bars 8 and tie rods 8^a (see particularly Figs. 2, 21 and 26) which, together with said heads, are mounted for limited vertical movements on two of the tie-rods 6 of said main register supporting frame. The said supplemental register supporting frame is, at least in part, supported by spring connections 9 (see Fig. 21) attached to the lower head 7^a and to the upper head 5. The said horizontal frame, of course, partakes of the horizontal rotary or oscillatory movements of the said main register supporting frame.

Vertical reciprocating movements of the said supplemental register supporting frame, in respect to the said main register supporting frame, is produced through means which will now be described in part, attention being directed particularly to Figs. 21 and 26.

The numeral 10 indicates a crank rod preferably made longitudinally adjustable, the lower end of which is pivotally connected to the lower head frame 7^a of the supplemental register supporting frame by a pin 10^a and the upper end of which is journaled 125

130

on a wrist pin 11^a of a short horizontal crank shaft 11 that is journaled in a bearing 12 rigidly secured to the upper head 5 of the main register supporting frame. This 5 crank shaft 11, at its outer end, is provided with a spur gear 13 that is operated upon by means hereinafter described. The crank shaft 11 has a disk-like flange 11^b formed at one point only with a notch 11^c that is normally engaged by a spring-pressed latch 14 intermediately pivoted to the upper head 5 and normally holding the wrist pin 11^a in a raised position, so that the said supplemental register supporting frame will be 10 normally held in raised position in respect to the main register supporting frame. The outer free end of the latch 14 has a notch 14^a for an important purpose which will hereinafter appear (see Fig. 26). Here it 15 may be further noted that the notched free end of the latch 14 is adapted to be depressed into a large clearance notch 5^a (see Figs. 24 and 26) formed in the upper edge of the annular outer rim of the upper head 5.

20 The registers or tallies are indicated, as entireties, by the numeral 15 (see particularly Figs. 24, 25 and 26) and their cases are rigidly secured to the channel bars 8 in vertical columns and preferably in an arrangement more fully disclosed in my two prior patents above identified. The unit member of each register is connected to move with a so-called escapement wheel 16 that is provided with ten laterally projecting triangular cam-acting escapement lugs 16^a. The 25 hubs 16^b that connect these escapement wheels 16 to the respective unit members of the registers is, in Figs. 24 and 25, shown as serrated or toothed for a purpose which need 30 not, however, be here considered, other than to state in a general way that it enables the register to be quickly reset.

For coöperation with each escapement wheel 16, there is provided an escapement 45 lever 17 that is pivoted at one end to a projection of the coöperating register case, and at its intermediate portion, is provided with laterally offset double-ended escapement lugs 17^a, the ends of which are reversely 50 beveled so that the escapement wheel will be given a half step, or one-half unit of rotation under downward movement of said lever and the second half step unit rotates under upward movement of said lever.

55 The number of register supporting bars 8, as well as the number of registers on each bar may, of course, be varied, but the total number of registers should, however, correspond to the number of register actuators 60 or keys in any one of the several sets to be hereinafter described.

The free ends of the escapement levers 17 project beyond upright bars 18 shown as of channel form, rigidly secured to the upper 65 and lower heads 5 of the main register sup-

porting frame; and these bars 18 are provided with lugs or lateral projections 18^a (see particularly Figs. 24, 25 and 26) with which the said levers are adapted to be engaged and by which said levers will be forced 70 downward when the supplemental register supporting frame is moved from its lower back to its normal or raised position. The registers above noted are, of course, for registering the individual votes cast by the 75 use of the machine.

Keyboard and register actuators or keys.

The register actuators or keys, which, as before stated, are arranged in vertical columns and in horizontal rows, are of the general arrangement and character disclosed and broadly claimed in my prior patents above identified and preferably are of the improved construction disclosed and claimed 80 in my companion application filed of even date herewith and entitled "Keyboard mechanism for voting machines".

In this preferred arrangement of the multiplex voting machine, the said register actuators or keys are arranged in three independent groups, so that three voters may independently set the register actuators in the respective groups in a manner which will 85 represent the total vote they desire to cast. 90

For the purposes of this case it is not necessary to describe in detail, all of the features of the said keyboard mechanism. In Fig. 27, a portion of one of the groups of 100 register actuators is shown in elevation and in Fig. 25^a, several of the register actuators and coöperating framework, are partly in elevation and partly in horizontal section. It may, however, be here further stated that the register actuators of the several groups 105 are in supplemental arrangement; that the supporting blocks or frame element therefor are contained in the vertical space between the lower head 1 and upper head 2 of the main frame, and within the annular space 110 between the inner and outer annular margins of said frames; and that what may be treated as the first group, in a circumferential direction, is between the columns 3^b and 3^c, that the second group, likewise, is between the columns 3^c and 3^d, and that the third group is between the columns 3^d and 3^a, attention being directed to Fig. 4, in which, for the sake of clearness, no attempt 115 has been made to show the said register actuators and escapement lever 17, as indicated in Figs. 25 and 26.

With the above comments, the said register actuators and immediately associated parts may be briefly described as follows; 125 attention being directed particularly to Figs. 1^a, 25, 25^a, 26 and 27.

Each complete register actuator comprises a register operating lever 19, and a finger actuated lever or key 20. The register actu- 130

ators are arranged in vertical columns and means will be provided for holding the ballot tickets in proper position adjacent to the respective rows of register actuators, all as 5 more fully disclosed in my prior Patent 1,158,518. For each vertical column of register actuators there is a vertical column of laterally expansible vote limiting devices made up of threaded hubs 21 and external 10 nut members 21^a, and which vote limiting devices may be properly of the character broadly claimed in my prior Patent 712,079, of date, October 28, 1902.

These vertical expansible vote limiting 15 elements 20 and 21 are rotatably mounted on the framework of the machine. Preferably, they are thus rotatably mounted in cylindrical seats formed in interlocking skeleton frame-forming blocks 22 best shown in 20 Fig. 25^a and disclosed and claimed in my companion application filed of even date herewith and entitled "Keyboard mechanism for voting machines". The levers 20 are rotatably mounted on hubs 23 (see Fig. 25^a) 25 which, in turn, are arranged in vertical columns upon so-called re-setting shafts 24. These re-setting shafts 24, as shown, are tubular and hexagonal and they are set upright and rotatably mounted in the base and 30 head structures of segmental frames 25 (see particularly Fig. 10). In the three-party voting machine, there are three of these segmental sections 25, which, when the machine is operative, are aligned in cylindrical arrangement. In practice, these segmental frame sections 25 will be arranged to swing into open positions, as disclosed in my prior Patent 1,039,419, of date, September 24, 1912. This swinging feature, however, constitutes no part of the present invention and 40 need not be further considered. The interlocking frame blocks 22^a, it should be understood, however, are secured to their respective segmental frames 25. As shown, the 45 said blocks 22^a are telescoped onto upright tubes 26, the upper and lower ends of which are anchored to the said segmental frames.

The hubs 23 are adapted to be given common rotary movements with the respective 50 shafts 24, through gears 27 (see Fig. 10) secured on the upper ends of the re-setting shafts 24. The pinions 27 of the re-setting shafts for each particular booth, or in other words, for each particular frame 25, mesh 55 with teeth on segmental racks 28 that are mounted for sliding movements on the arc of curves through keepers 29 secured on the lower plates of the upper portions of the said frames 25. The means for imparting 60 sliding movements to the respective racks 28 will be hereafter described.

The lever 20 of each register actuator has a projecting arm with a pin 30 that works in the slotted arm of the lever 19 of the same 65 actuator (see Fig. 25^a). In Fig. 25^a, the reg-

ister actuator at the right is in its set or operative position. In this set or operative position shown at the right, the projecting end of the lever 19 will be thrown directly under the escapement lever 17 of the corresponding register or tally, providing the register support has been properly positioned for registration of votes. This action will be more fully brought out in the description of the operation. It will, of course, be understood 70 that the finger-actuated lever or key 20 will be moved from its normal position at the left into its set position at the right, by the finger of the voter.

To restore the set register actuators to 80 normal positions by rotary or oscillatory movements of the re-setting shafts 24, the hubs 23 are provided with projecting lugs 31 (see Fig. 25^a) that are engageable with depending lugs 32 on the levers 20. This operation, also, will be more fully disclosed in 85 the description of the operation.

Judge actuated devices, voter's registering crank and coöperating mechanism.

For oscillating the rotary register support so as to carry the registers into alinement with any one of the three groups of register actuators, there is provided a so-called positioning crank (see particularly Figs. 2, 3, 4 and 5) which is located between two of the booths and in position to be easily reached by the election judge or attendant, but by no one of the three voters from within the booths. This crank 33 is secured to 90 the outer end of a radial shaft 34 journaled in suitable bearings on the upper head 2 of the machine frame and provided at its inner end with a beveled pinion 35 that meshes with a beveled gear 36 secured to the shaft 100 4 of the said rotary register support. This crank 33 (see Fig. 3) has a spring-pressed lock pin 37 that is adapted to engage a lock notch 38^a in a lock disk 38 that is rigidly secured to the said upper head 2. Whenever 105 the lock pin 37 is engaged with the lock seat 38^a, the registers will be secured in proper position for coöperation with one or the other of the three independent sets of register actuators. Otherwise stated, one 110 rotation of the crank 33 will move the registers from alinement with one set of register actuators.

On the upper or head portion of each of the three segmental frames 25 is a short radial shaft 39 (see particularly Figs. 10, 11, 12, 17, 18, 19 and 26) which, at its outer end, is provided with a so-called voter's registering crank 40. This crank 40, when the machine is free for the registration of votes by 115 the voter, stands in the position indicated by full lines in Figs. 11 and 27, and is then held against the upper edge of a stop 41 on the upper head of the corresponding segmental frame 25. From this it will, of course, be 120 125 130

understood that there is one of these cranks 40 exposed within each booth or at the front of each set of register actuators. The shaft 39, near its outer portion, is mounted for 5 rotary movements and for limited vertical oscillatory movements, by means of a ball surface 39^a thereon which works in a socket plate 42 (see Figs. 10, 15 and 16) secured on the head of the said frame 25. Adjacent to 10 its extreme inner end the shaft 39 is provided with a spur gear 43 (see Figs. 10, 12, and 26) that is slightly larger than the gear 13. Otherwise stated, said gear 43 is of such size that when the voter's crank 40 is 15 moved from a full line position into the dotted line position in Fig. 27, the said gear 13 and crank driven thereby, will be given one complete rotation.

That portion of the shaft 39 that is adjacent to the gear 43 extends through a cam slot 44 of a cam plate 45 mounted to slide horizontally in a bearing block 46 formed as a part of the head of the frame 25, (see particularly Figs. 10, 18 and 19). When the 25 cam plate 45 is at the right, as shown in Fig. 18, cam groove 44, operating on shaft 39, will raise gear 43 above a position in which it will engage with gear 13, providing the latter is then positioned thereunder; but 30 when cam plate 45 is moved to the left, as shown in Fig. 19, cam groove 44, operating on shaft 39, will lower gear 43 into mesh with gear 13, providing the latter is then positioned under the same.

35 On one face, the cam plate 45 has a laterally projecting lug 47. The gear 43, on that face that is adjacent to that face of the slide 45, has a lug 47. In Figs. 18 and 19, the said lugs 48^a and 48^b are shown in section and 40 the disk 48 is removed.

Pivoted to the upper portion of the bearing plate 46 is a latch 49 which has a depending lug 49^a and laterally projecting latch pin 49^b, which latter, under certain 45 conditions, will drop into the dotted line position in Fig. 18 and lock the cam plate 45 in the position shown in Fig. 18.

The disk 48 (see Fig. 20) at one point, is provided with a lock shoulder 48^c which, 50 when the voter's registering crank 40 is in the position shown in Fig. 11, is engaged by the free end of a lock dog 50; and hence, that when the inner end of the shaft 39, together with the gear 43 and disk 48, which are carried thereby, are dropped the lock shoulder 48^c will be carried below and disengaged from said dog and the crank 40, thereby released, so that it may be moved by the voter, as hereinafter described. It will, of course, 55 be understood that the parts just described in the singular are provided in like manner for each of the three sections, or keyboards of the machine.

60 Mounted in suitable bearings on the head 65 of the frame of each segmental frame 25, not

far distant from the corresponding shaft 39, is a radial rock shaft 51, which, at its inner end, is provided with a projecting arm 52 shown as equipped with a roller 52^a. Near its front end, said shaft 51 is provided with 70 a segmental chain drum 53. This drum segment 53 is provided with a laterally projecting segmental cam flange 54. A ratchet wheel 55 is secured to the shaft 39 near its front end, and a chain, preferably a quite 75 heavy link chain 56 is connected to its ratchet wheel and to the segmental chain drum 53 (see Figs. 10 and 11). This ratchet wheel 55 constitutes part of a so-called full stroke device, and it is adapted to be engaged by the 80 pawl-acting end of a lock lever 57 that is pivoted to a bearing on the head of the corresponding segmental frame 25 (see Figs. 10 and 11). At its projecting end, the lever 85 or dog 57 has a laterally projecting pin 57^a which, in the position of the parts shown in Fig. 11, rides on the segmental flange 54 of the drum 53 and holds the said dog out of action on the ratchet wheel 55, under an operation which will be further considered. 90

The shaft 51 has a lock shoulder 51^a, which, in the position of the parts shown in Fig. 19, is adapted to be engaged by the relatively short and light end of a lock dog 58 pivoted to a part of the head of the 95 frame 25. The long and relatively heavy end of this lock dog 58 has a laterally projecting pin or lug 58^a which, when the slide 45 is at the right, as shown in Fig. 18, is engageable thereby, so as to release the said 100 dog from the shoulder 51^a, and hence, releases shaft 51.

At its intermediate portion, each of the three shafts 39 has a worm or cam-acting spiral 59 (see Fig. 10). The cam flange of 105 this worm 59 works between the prongs of a bifurcated lever 60 secured to the upper end of a short upright rock shaft 61 suitably journaled to the head of the corresponding frame 25 and having at its lower end an 110 arm 62 that is pivotally connected to the co-operating segmental rack 28.

The three keyboards will be numbered 1, 2 and 3; and for each keyboard or complete set of register actuators, there is a so-called 115 judge's lock controlling lever. Of these levers, lock lever for keyboard No. 1, is marked L¹; that for keyboard No. 2, L²; and that for keyboard No. 3, L³ (see Fig. 6). These three levers are secured, respectively, to the lower ends of three concentric upright shafts m¹, m², and m³, and are journaled in suitable bearings on the fixed frame structure. At their upper ends, the shafts m¹, m², and m³, respectively, are provided with short arms n¹, n², and n³ (see Figs. 5 and 6), and these arms n¹, n², and n³, respectively, are connected to the ends of overlying trussed or skeleton-like levers p¹, p², and p³. These three levers p¹, p², and 120 p³ are connected to the ends of overlying trussed or skeleton-like levers p¹, p², and p³. These three levers p¹, p², and 125 p³ are connected to the ends of overlying trussed or skeleton-like levers p¹, p², and p³. These three levers p¹, p², and 130 p³ are connected to the ends of overlying trussed or skeleton-like levers p¹, p², and p³.

p^3 , are all pivoted on the upper portion of the shaft 4 and their ends work through slotted guide plates 63 and 64 (see Figs. 7 and 8) secured on the upper frame head or bracket 3. As shown in Fig. 8, a yielding spring-pressed beveled nose pin 65 prevents accidental movements of the said levers. Here it may be noted that the lever p^2 is a diametrically extended lever, while the levers p^1 and p^3 are sort of ball cam levers with their ends projecting in opposite direction. The free ends of the three levers p^1 , p^2 , and p^3 , all, in like manner, terminate in heads 66 which perform like operations on the slides 45 and arms 52 of the co-operating mechanisms above described and preferably illustrated in Figs. 10, 11, 12, 18, 19 and 20. By reference to Figs. 18 and 19, it will be seen that the particular head 66 works directly between the right hand end of the plate 45 and the roller 53 of arm 52.

To enable the voter to readily give the election judge the signal when he is ready to cast his vote, a so-called signaling arm 67 (see Figs. 1, 1^a and 27 to 29, inclusive) is provided. The three signaling arms are marked, the one with the numeral 1, another with the numeral 2, and the other with the numeral 3, to indicate the number of the keyboard or booth. Each is provided with a sleeve-like hub 68 that is loosely pivoted on the outer end of the shaft 39 adjacent to the hub of the lever 40.

The signaling arm 67 is movable from a horizontal to a vertical position, and vice versa, between stops 67^a and 67^b. The hub 68 of the signaling arm 67 is provided with a lightly spring-pressed friction pin 67^c (see Fig. 29) which slightly increases the friction between the same and the shaft 39 of the voter's operating crank 40. The external surface of the hub 68 is also frictionally engaged by a lightly spring-pressed friction pin 68^a mounted in a fixed block 68^b (see Figs. 27, 30 and 31). The friction produced by the pin 67^c is sufficient to cause the signaling arm 67 to drop from its raised position when crank 40 is moved from its full line to its dotted line position in Fig. 27, but is not sufficient to cause the said arm to return to said crank and shaft 39 because the said arm, when in a horizontal position, exerts very much greater resistance and movement of the said crank.

Figs. 32, 33 and 34 illustrate a lock for locking the register positioning crank 33, so that the register support cannot be moved when the machine is closed. This lock, as shown, comprises a pair of lock bolts 69 secured to a head 70, mounted to slide in suitable bearings on the inner side of one of the fixed plates 3^a of the fixed framework. Normally, the lock bolts are retracted as indicated by full lines in Fig. 34, but when they are projected, as indicated by dotted

lines in Fig. 34, they will positively lock the crank 33 against movement. To readily move the lock bolts 69 to and from retracted positions, an upright shaft 71 is also mounted in suitable bearings on the inner surface 70 of the frame plate 3^a. At its lower end, this shaft 71 has an operating crank 72, and at its upper end, it has a head 73 that carries a crank pin 73^a working in a transverse slot of the head 70. The shaft 71 and its crank 72 are inside of the machine case and it is evident that it cannot be reached when the machine case is closed and locked up.

In this improved machine, I preferably provide a so-called total vote register, in fact, I preferably provide two total vote registers, one of which is concealed within the machine when wings b are closed, but is visible to the voter when the machine is in operation, and the other of which total vote registers is exposed where it may at any time be viewed but not manipulated from the exterior of the machine, regardless of whether or not the machine is closed up.

The first noted total vote register will first be described, attention being directed particularly to Figs. 24 to 38.

This total register is preferably of the same general character as the registers or tallies 15, and is indicated, as an entirety, by the numeral 74. Its case is rigidly secured to one of the channel bars 8. The unit member of this register is connected to move with a so-called escapement wheel 75 that is provided with ten laterally projecting triangular cam-acting escapement lugs 75^a. For co-operation with each escapement wheel 75 there is provided an escapement lever 77 that is pivoted at one end to a projection of the register case and, at its intermediate portion is provided with laterally offset double-acting escapement lugs 77^a, the ends of which are reversely beveled, so that the escapement wheel will be given a half step under upward and a second half step of rotation under downward movement of the lever 77. The end of said lever 77 works through a slot 78 formed in the adjacent relatively fixed channel bar 18.

The latter noted or second externally exposed total vote register is best shown in Figs. 1^a, 35, 36 and 37, and, in its general character, is like the other registers and is indicated as an entirety, by the numeral 79. The case of this total vote register has an offset hub 79^a that is rigidly secured to the extreme upper end of the upright axial shaft 4 to which the main frame of the register support is secured. The unit member of this total vote register 79 is secured to rotate with an escapement wheel 80 having ten cam-acting escapement lugs 80^a. For co-operation with this escapement wheel, an escapement lever 81 is pivoted to the hub 79^a and at its free end, is provided with a

laterally offset double-ended escapement lug or head 81^a, the ends of which are reversely beveled so that the escapement wheel will be given one-half step of rotation under upward movement and the second half step of rotation under downward movement of the said escapement lever 81. The escapement lever 81 is connected by a rod and link 82 to a spring arm 83, one end of which is attached to the upper head bracket 5 of the vertically movable supplemental frame of the register support. To indicate the position of the register support, the hub or head 79^a is provided with a long radially projecting pointer or indicator arm 84 (see Figs. 1, 1^a, 2 and 35). The position of this arm 84 will indicate with which of the three keyboards or sets of register actuators, the common rotatively movable set of registers 20 is positioned for coöperation.

Operation.

The operation of the machine, summarized, is as follows:

When the voter enters one or any of the booths the signaling arm 67 will be turned down into its horizontal position indicated by dotted lines in Fig. 27. Also, at this time, certain other parts of the machine will be positioned as follows:

The voter's operating crank will be in the position indicated by full lines in Figs. 12 and 27. The register actuators or keys will be in the positions indicated at the left in Fig. 25^a, but by the voter may be moved at will into the set position indicated at the right in Fig. 25^a. In this set position of the actuators the projecting inner ends of the set levers 19 will stand immediately under the escapement levers 17 of the corresponding registers, providing the common set of registers, at such time, happens to be properly positioned. However, the said common set of registers can occupy a coöperating relation to the set registers of only one set of register actuators at one time, but regardless of this the set actuators are positioned so that they will occupy the above noted relative operative positions on the escapement levers 17 whenever the set of registers is properly positioned for coöperation therewith. This action, however, is broadly and more fully disclosed in my prior Patent No. 1,158,518, and the said patent also includes the manner in which, by suitable vote limiting devices, the voter is prevented from casting too many votes for any one office. For the purpose of this case, it is only necessary to further state that when the voter has set those register actuators or keys that represent his total vote, no actual registration of votes has yet taken place and that before this can take place, the voter, by turning up the signaling arm 67 into the position shown in Fig.

27, signals to the attendant of the machine that he is ready to cast his vote. Up to or at this time, the voter's operating crank 40 remains locked in its full line position (Figs. 11 and 27) by the dog 50, (see particularly Fig. 20) which then engages the notch of the disk 48.

When the attendant receives the signal indicating that the voter is ready to cast his vote, first by giving the positioning crank 75 33 one or two rotations, as the case may require, rotates the common set of registers into coöperative position in respect to the set of actuators from which the signal has come. This not only properly positions the 80 escapement lever 17 of the register actuators in respect to the levers 19 of the set actuators, but also moves the notch 14^a of latch 14 into alignment with the projecting end of the shaft 39 which belongs to the 85 corresponding group of actuators.

The next operation performed by the attendant or judge is to move the proper one of three judges' levers L¹, L² or L³, as the case may be, so as to thereby cause the corresponding lever head 66 to move from the position indicated in Fig. 18 into the position indicated in Fig. 19. This movement of the head 66 moves the cam block 45 from the position indicated in Fig. 18 into the 95 position indicated in Fig. 19 and the cam groove 44 thereof, then throws the inner end of shaft 39 downward. This downward movement of the rear end of the shaft 39 (see Fig. 26) performs two important functions, to wit, first it depresses the outer end of latch 44, raises inner end thereof out of engagement with notch 11^a of disk 11^b and thereby releases the crank 11^a, shaft 11 and gear 13, and second, and at the same time, 100 it lowers gear 43 of shaft 39 into mesh with gear 13 of shaft 11. This releases the voter's crank 40.

In the position of the parts shown in Fig. 11, in which position the voter's crank 40 110 is in normal position, the dog 57, by a flange 54 of segment 53 is held out of engagement with latch wheel 55, but initial movement of crank 40 pulling on chain 56, will cause the weight of the chain to quickly throw 115 the segment 53 into its dotted line position Fig. 11. In fact, the weight of the said chain may accomplish this result even before initial movement is imparted to crank 40. As soon as segment 53 is thrown to its 120 dotted line position, Fig. 11, dog 57 is released, and, acting on ratchet wheel 55, will prevent backward rotation of crank 40 until said crank has been moved to its extreme position indicated by dotted lines in Fig. 125 27. Thus, pawl 57 and ratchet wheel 55 serve as a full stroke device for crank 40.

Movement of the operator's crank, which is performed by the voter, from full line position to dotted line position, Figs. 11 130

and 27, imparts one complete rotation to crank shaft 11, and thereby first lowers and then again raises back to normal position, the supplemental vertically movable frame 5 7-7^a of the oscillating register support. The downward movement of the said supplemental register supporting frame carries the end of the escapement lever 17 down onto the projecting levers 19 of the set actuators, thereby imparting the first half step of rotation to registers that are operated on by the set actuators. The second half step of rotation is imparted to the said escapement levers by the upward movement of 10 the said frame which carries the escapement levers 17 against the lugs 18^a of the relatively fixed bars 18 of the main frame of the oscillatory register support. The above noted movement of operating crank from 15 full line to dotted line position accomplishes several other important functions. Under the above noted rotation of said crank, gear 43, rotating in the direction of the arrow marked thereon in Figs. 18 and 19, will 20 cause pin 48^a to strike lug 47, and thereby return slide 45 to position shown in Fig. 18. This return movement of the slide 45 raises the inner end of shaft 39, thus disengaging gear 43 from gear 13 and releasing 25 latch 14, so that it locks crank shaft 11 immediately upon completion of its rotation back to normal position, Fig. 26. In Fig. 30 18, position occupied by pin 48^a in completing return movement of slide 45 is indicated by dotted lines. Also, position of pin 48^b, at the same time, to wit, while voter's crank 40 is in dotted line position, Fig. 27, is indicated by dotted lines in Fig. 18, by reference to which it will be further noted that 35 40 at this time, pin 48^b permits latch 49 to drop and its pin 49^b to temporarily lock slide 45 in position shown in Fig. 18.

It has now been seen that the slide 45 is 45 restored to normal position, Fig. 18, by the movement of the voter's crank from normal to dotted line position, as above described. The voter's operating crank, however, at the completion of movement from full line to dotted line position, is still locked by the 50 dog 57 of the full stroke device, and before voter's crank 40 can be returned to normal position, this dog 57 must be released from ratchet wheel 55. To release dog 57 from ratchet wheel 44 requires a return movement 55 of chain segment 53 from dotted line back to full line position, Fig. 11, and this operation can not be performed by the voter but only by the attendant. The attendant 60 accomplishes this return movement by moving the proper lever L¹, L², L³, as the case may be, so as to force the cooperating head 66 from the position indicated in Fig. 18 to the right far enough to carry the roller-equipped lever 52 from full line position to 65 dotted line position, Fig. 18. The initial

part of the return movement of the chain segment 53 causes cam flange 54 to release dog 57 from ratchet wheel 55, and moreover, the said return movement of segment 53 pulls on chain 56, turns voter's crank 40 70 back to normal position where it becomes immediately and automatically again locked by the dog 50.

It has been noted that dog 57 prevents backward rotation of ratchet wheel 55, and hence, of crank 40 until after chain segment 53 has been returned from dotted line to full line position, Fig. 11, and in this connection, it is important to note that whenever slide 45 is at the left of its normal position, Fig. 18, dog 58, anchoring shoulder 51^a of shaft 51 locks said shaft, and hence, the chain segment 53 in dotted line position, Fig. 11. This makes it impossible even for the election judge to return chain segment 53 and crank 40 to normal position until after said crank 40 has been moved completely to dotted line position Fig. 27, and at the completion of that movement slide 45 is again restored to its 80 normal position, Fig. 18, and in that position only, releases dog 58 from the shoulder 51^c of said shaft, 51.

The action of lock dog 49 has probably 90 been clearly described but attention is called to the fact that the only time that it locks slide 45 is when voter's lever is in the dotted line position (Fig. 27). When the machine is locked and out of action, the voter's crank will be left in said dotted line position, and hence slide 45 will be locked at that time.

Attention is further called to the fact that when voter's crank 40 is moved from its full line to its dotted line position, Fig. 105 27, signaling arm 67 will be dropped back to its dotted line horizontal position. When the voter's crank 40 is in the full line position (Fig. 27) lugs 31 of hubs 23 will be in position in Fig. 25^a.

By reference to Fig. 25^a, it will be noted, 110 that when the register actuator is moved from its normal position at the left into a set position at the right, the depending lugs 32 on levers 20 follow up and nearly or quite engage with lugs 31 of the hubs 23, which hubs partake of rotary movement of the respective shafts 24.

Resetting of these actuators back to normal position is produced as follows:

When voter moves crank 40 from normal to dotted line position (Fig. 27) cam flange 59 (Fig. 10), acting on forked head 60 will oscillate shaft 61 and arms 62, thereby moving the segmental rack 28 of that group of 125 actuators and, through pinions 27, will simultaneously move all of the shafts 24 of that group of actuators in a reverse to clock-wise direction, in respect to the Fig. 25^a, thereby causing the lugs 31, by engage- 130

ment with lugs 32, to simultaneously restore all of the register actuators to normal positions. In these positions, the said lugs 31 will remain as long as voter's crank 40 is in its dotted line position, Fig. 27. Hence, when voter's crank 40 is in the said dotted line position, all of the actuators are locked in inoperative positions. Here it will be remembered that these actuators are released by the attendant manipulating the proper one of the levers L^1 , L^2 , L^3 , so as to thereby force the coöperating slide 45 from its normal position at the right into a position toward the left. Here it may be stated, that this operation may take place either just before, or just after a voter enters the booth, but must, of course, take place before the voter can manipulate the keys or actuators.

20 Here it may be further recalled that each movement downward and return of the supplemental frame of the register carrier, not only registers the votes represented by the set actuators on the corresponding individual 25 vote registers, but simultaneously operates both of the total vote registers.

What I claim is:

1. In a voting machine, the combination with a set of vote registers and a coöperating set of register actuators, of a movable voter's operating hand piece with connections whereby movement thereof from normal position will cause the set actuators to operate coöperating registers, a lock normally holding the said voter's hand piece in normal position, and a judge's lever having two movements and combined connections whereby movement in one direction will release said voter's hand piece and 40 movement in the opposite direction will restore said voter's hand piece to normal position.

2. In a multiplex voting machine, the combination with a common set of vote registers and a movable support therefor, of a multiplicity of coöperating sets of register actuators, a voter's operating hand piece for each such set of register actuators, combined with connections whereby movement thereof in one direction will render the set actuators operative on corresponding vote registers, a lock normally holding said hand piece in normal position, and a judge's lever for each set of register actuators combined 55 with connections whereby movement of the proper one of said judge's levers in one direction will release said lock and movement in the other direction will restore said voter's hand piece to normal position.

60 3. In a voting machine, the combination with a set of vote registers and a coöperating set of register actuators, of a voter's operating crank and coöperating connections whereby movement of said crank from normal position will render the set actuators

operative on corresponding registers, a lock normally holding said voter's crank in normal position, and a judge's lever and coöperating connections whereby movement of said lever in one direction will release said lock and movement thereof in the opposite direction will oscillate said voter's crank to normal position.

4. In a voting machine, the combination with a set of vote registers and a coöperating set of register actuators, of a voter's operating crank and coöperating connections whereby movement of said crank from normal position will render the set actuators operative on corresponding registers, 75 a lock normally holding said voter's crank in normal position, and a judge's lever and coöperating connections whereby movement of said lever in one direction will release said lock and movement thereof in the opposite direction will oscillate said voter's crank to normal position, and a full stroke device for said voter's crank operative under movement of the latter from normal position but arranged to be released by the initial part of that movement of said judge's lever which serves to restore said voter's crank to normal position.

5. In a voting machine, the combination with a set of vote registers and coöperating 95 set of register actuators, of a voter's operating crank and coöperating connections whereby movement of said crank from its normal position will render the set actuators operative on corresponding registers, 100 a lock normally holding said voter's crank in normal position, a ratchet wheel movable with said crank, a dog coöperating with said ratchet wheel, a cam-equipped oscillating member operative on said dog to release 105 the same from said ratchet wheel, in one position, a flexible connection between said oscillating member and said voter's crank, and a judge's lever combined with connections whereby, under movement in one direction, it will release said lock and permit 110 said voter's crank to be operated by the voter and under movement in the other direction will move said oscillating cam member in a direction first to release said dog 115 from said ratchet wheel and then to restore said voter's crank to normal position.

6. In a voting machine, the combination with a set of vote registers and coöperating set of register actuators, of a voter's operating crank and coöperating connections whereby movement of said crank from its normal position will render the set actuators operative on corresponding registers, a lock normally holding said voter's crank in normal position, a ratchet wheel movable with said crank, a dog coöperating with said ratchet wheel, a cam-equipped oscillating member operative on said dog to release the same from said ratchet wheel, in one position,

tion, a flexible connection between said oscillating member and said voter's crank, a judge's lever combined with connections whereby under movement in one direction, 5 it will release said lock and permit said voter's crank to be operated by the voter and under movement in the other direction will move said oscillating cam member in a direction first to release said dog from said 10 ratchet wheel and then to restore said voter's crank to normal position, and a lock for said oscillating cam member arranged to lock the same while said voter's crank is in normal position, or in an intermediate position, but 15 is, itself, released when said voter's crank is in an extreme position from normal.

7. In a multiplex voting machine, the combination with several sets of register actuators, of a common set of vote registers 20 and a movable support therefor, means for moving said register support to position said registers for coöperation with any of said group of actuators, means comprising a gear carried by said register support for imparting 25 common vertical movements to said registers to thereby render the set actuators operative thereon, a voter's crank for each group of actuators, said crank having a vertically movable shaft and a gear thereon 30 for coöperation with the gear on said register support, a lock disk on said shaft, a lock dog operative thereon only when said shaft is raised and released therefrom when said shaft is lowered, a cam slide for each set of 35 actuators operative on the corresponding voter's crank shaft to raise and lower the same, and a voter's lever having connections for moving said slide in one direction, the complete movement of said voter's crank 40 from normal position serving to restore said slide to its normal position.

8. In a voting machine, the combination with a set of register actuators and a co-operating set of vote registers, means comprising a gear mounted on the register support for imparting common vertical movement to said vote registers to thereby render the set actuators operative thereon, a voter's crank having a vertically movable shaft 45 equipped with a gear for co-operation with the gear on said register support, a cam slide operative on said shaft to raise and lower the same, a lock disk on said shaft, a lock dog co-operating with said lock disk to lock 50 said shaft and voter's crank in normal position when said shaft is raised but released therefrom when said shaft is lowered, and a judge's lever having connections operative 55 on said slide to move the same in a direction to lower said shaft, and means whereby completion of the movement of said voter's crank from normal position will restore said slide to its normal position and raise said shaft, thereby disconnecting the said gears. 60 65 9. In a voting machine, the combination

65 9. In a voting machine, the combination

with a set of register actuators and a co-operating set of vote registers, means comprising a gear mounted on the register support for imparting common vertical movement to said vote registers to thereby render the set actuators operative thereon, a voter's crank having a vertically movable shaft equipped with a gear for coöperation with the gear on said register support, a cam slide operative on said shaft to raise and lower the same, a lock disk on said shaft, a lock dog coöperating with said lock disk to lock said shaft and voter's crank in normal position when said shaft is raised but released therefrom when said shaft is lowered, a rock shaft having an arm and a chain sheave, and coöperating means connecting said chain sheave to said voter's crank, a judge's lever having two movements and combinations with connections whereby movement thereof in one direction will move said slide from normal position and lower said voter's crank shaft, thereby connecting said gears, and movement thereof in the other direction will engage the arm of said rock shaft, and through said chain, restore said voter's crank to normal position, and means whereby the completion of movement of said voter's crank from normal position will restore said slide to normal position, thereby raising said voter's crank shaft and disconnecting said gears.

10. In a voting machine, the combination with a set of register actuators and a coöperating set of vote registers, means comprising a gear mounted on the register support for imparting common vertical movement to said vote registers to thereby render the set actuators operative thereon, a voter's crank having a vertically movable shaft equipped with a gear for coöperation with the gear on said register support, a cam slide operative on said shaft to raise and lower the same, a lock disk on said shaft, a lock dog coöperating with said lock disk to lock said shaft and voter's crank in normal position when said shaft is raised, but released therefrom when said shaft is lowered, a rock shaft having an arm and a chain sheave and coöperating means connecting said chain sheave to said voter's crank, a judge's lever having two movements and combinations with connections whereby movement thereof in one direction will move said slide from normal position and lower said voter's crank shaft, thereby connecting said gears, and movement thereof in the other direction will engage the arm of said rock shaft and through said chain restore said voter's crank to normal position, means whereby the completion of movement of said voter's crank from normal position will restore said slide to normal position, thereby raising said voter's crank shaft and disconnecting said gears, and a lock securing said rock shaft 130

against movement when said slide is moved from normal position, the said lock being released when said slide is in normal position.

11. In a voting machine, the combination 5 with a set of register actuators and a coöperating set of vote registers, means comprising a gear mounted on the register support for imparting common vertical movement to said vote registers to thereby render the set 10 actuators operative thereon, a voter's crank having a vertically movable shaft equipped with a gear for coöperation with the gear on said register support, a cam slide operative on said shaft to raise and lower the same, a lock disk on said shaft, a lock dog coöperating 15 with said lock disk to lock said shaft and voter's crank in normal position when said shaft is raised, but released therefrom when said shaft is lowered, a judge's lever 20 having connections operative on said slide to move the same in a direction to lower said shaft, means whereby completion of the movement of said voter's crank from normal position will restore said slide to its normal 25 position and raise said shaft, thereby disconnecting the said gears, a lock securing said slide in normal position when the voter's crank is moved from normal position, and a lock securing said slide in normal position 30 when said voter's crank is in extreme position from normal, but released from said slide when said voter's crank is in normal position.

12. In a voting machine, the combination 35 with a set of register actuators and a coöperating set of vote registers, means comprising a gear mounted on the register support for imparting common vertical movement to said vote registers to thereby render the set 40 actuators operative thereon, a voter's crank having a vertically movable shaft equipped with a gear for coöperation with the gear on said register support, a cam slide operative on said shaft to raise and lower the same, a lock disk on said shaft, a lock dog coöperating 45 with said lock disk to lock said shaft and voter's crank in normal position when said shaft is raised but released therefrom when said shaft is lowered, a rock shaft having an arm and a chain sheave and coöperating means connecting said chain sheave to said voter's crank, a judge's lever having two movements and combinations with connections whereby movement thereof in one 50 direction will move said slide from normal position and lower said voter's crank shaft, thereby connecting said gears, and movement thereof in the other direction will engage the arm of said rock shaft and 55 through said chain restore said voter's crank to normal position, means whereby the completion of movement of said voter's crank from normal position will restore said slide to normal position, thereby raising said 60 voter's crank shaft and disconnecting said 65

gears, a lock securing said rock shaft against movement when said slide is moved from normal position, the said lock being released when said slide is in normal position, a lock securing said slide in normal position when 70 the voter's crank is moved from normal position, and a lock securing said slide in normal position when said voter's crank is in extreme position from normal, but released from said slide when said voter's crank is in 75 normal position.

13. In a voting machine, the combination with a set of register actuators and a coöperating set of vote registers, means comprising a gear mounted on the register support 80 for imparting common vertical movement to said vote registers to thereby render the set actuators operative thereon, a voter's crank having a vertically movable shaft equipped with a gear for coöperation with 85 the gear on said register support, a cam slide operative on said shaft to raise and lower the same, a lock disk on said shaft, a lock dog coöperating with said lock disk to lock said shaft and voter's crank in normal 90 position when said shaft is raised but released therefrom when said shaft is lowered, a judge's lever having connections operative on said slide to move the same in a direction to lower said shaft, means whereby 95 completion of the movement of said voter's crank from normal position will restore said slide to its normal position and raise said shaft, thereby disconnecting the said gears, a ratchet wheel carried by said voter's crank 100 shaft, a dog coöperating with said ratchet wheel, and a cam carried by said rock shaft, said ratchet wheel, dog and cam constituting a full stroke device for said voter's crank and operating substantially as described. 105

14. In a voting machine, the combination with a set of register actuators and a coöperating set of vote registers, means comprising a gear mounted on the register support for imparting common vertical movement to 110 said vote registers to thereby render the set actuators operative thereon, a voter's crank having a vertically movable shaft equipped with a gear for coöperation with the gear on said register support, a cam slide operative 115 on said shaft to raise and lower the same, a lock disk on said shaft, a lock dog coöperating with said lock disk to lock said shaft and voter's crank in normal position when said shaft is raised, but released therefrom 120 when said shaft is lowered, a judge's lever having connections operative on said slide to move the same in a direction to lower said shaft, means whereby completion of the movement of said voter's crank from normal position 125 will restore said slide to its normal position and raise said shaft, thereby disconnecting the said gears, a ratchet wheel carried by said voter's crank shaft, a dog coöperating with said ratchet wheel, a cam carried by 130

- said rock shaft, said ratchet wheel, dog and cam constituting a full stroke device for said voter's crank and operating substantially as described, and a lock operative to secure said 5 slide in normal position when said voter's crank is in an extreme position from normal, but arranged to be released therefrom when said voter's crank is in normal position.
15. In a voting machine, the combination 10 with a set of vote registers and coöperating set of register actuators, of a movable voter's operating hand piece with connections whereby movements thereof from normal position will cause the set actuators to operate corresponding registers, and actuator restoring means comprising a cam moved by said hand piece, and an oscillating member subject to said cam and having connections for operation on said actuators.
- 20 16. In a voting machine, the combination 15 with a set of vote registers and a coöperating set of register actuators, of a voter's operating crank and connections for causing set actuators to operate corresponding vote registers, a spiral cam operated by said hand piece, shafts provided with devices engageable with said actuators to re-set the same, sliding bars with connections for simultaneously oscillating said shafts, and an oscillating member operative on said sliding bar and subject to said spiral cam to restore set actuators to normal position under movement of said voter's crank.

17. In a voting machine, the combination 35 with a set of vote registers and a coöperating set of register actuators, of a voter's operating crank and connection for causing set actuators to operate corresponding vote registers, a spiral cam operated by said hand piece, shafts provided with devices engageable with said actuators to re-set the same, pinions on said shafts, a rack engageable with said pinions and an oscillatory member operated upon by said spiral cam and connected to said rack for reciprocating the 45 same and thereby simultaneously restoring set actuators to normal position under movement of said voter's crank.

18. In a multiplex voting machine, the 50 combination with a casing and frame, of a plurality of sets of register actuators, a common set of vote registers, a register support movable to position said common set of actuators for co-action with any of said several sets of vote actuators, means for moving said register support comprising a hand piece at the exterior of said casing, and a lock mechanism located within said casing and operative to secure said hand piece in a 55 fixed position.

In testimony whereof I affix my signature in presence of two witnesses.

SYVER LOE.
